UNITED STATES PATENT OFFICE.

ROBERT N. BAYLIS, OF CALDWELL, NEW JERSEY, ASSIGNEE TO THE BAYLIS COMPANY, OF BLOOMFIELD, NEW JERSEY, A CORPORATION OF NEW JERSEY.

COMMUTATOR BRUSH.

Application filed June 24, 1924. Serial No. 721,992.

To all whom it may concern:

Be it known that I, ROBERT N. BAYLIS, a citizen of the United States of America, residing at Caldwell, New Jersey, have invented a new and useful Commutator Brush, of which the following is a specification.

My invention relates to a new and useful improvement in a commutator brush of a certain type, which improvement results in greatly prolonging the life of such a brush. The particular brush to which my improvement relates is of the type shown and described in my former Patent No. 504,901, of September 12, 1893, in which patent will also be found a detailed description of the holder adapted to said brush.

In the accompanying drawings—

Fig. 1 is a side elevation of my improved brush as it would appear in use, a brush holder and a portion of a commutator being conventionally shown;

Fig. 2 is a perspective view of the brush alone;

Fig. 3 is a side elevation of the brush alone.

a represents a block of electrical conducting material, preferably carbon, which constitutes the commutator brush proper. *b* represents the body of the brush holder. *f* represents a stationary supporting pin or stud for said brush holder. *c* represents a presser arm which engages the upper or outer end of the brush *a*, for holding it in position against the face of the brush holder body *b* and for feeding the brush against the commutator *d*. Ordinarily, the arm *c* of the brush holder is impelled forwardly by means of a spring (not shown), such as fully described in my former patent and now well understood in the art.

In the particular form shown herein the brush supporting face of the holder body *b* is placed at an incline relatively to the surface of the commutator *d*, in a plane between the tangent and the radius of the commutator. This is, perhaps, the most common practice, although the particular angle of the brush supporting face relatively to the commutator is not material. With the body *b* set as shown in Fig. 1, the inner contact end of the brush *a* would necessarily be formed at an appropriate angle to properly contact with the surface of the commutator *d*, as shown in Fig. 1. The upper or outer end of the brush *a*, in order to be

properly held against the supporting face of the brush holder by the arm *c*, has heretofore been formed on an incline or bevel extending from the front to the rear edge, as may be seen by reference to Fig. 10 of my aforesaid patent. It is obvious that if this bevel at the outer end of the brush *a* extends entirely across the block from the point *x* to the point *y*, as in my previous patent, the effective life of the brush will end when it is worn down to the dotted line *w—y*. I have found that by cutting away only a portion of the outer end of the brush, so as to form an incline or bevel which extends partially across the same, as shown clearly in the drawings, I can very materially add to the effective life of said brush, since it is apparent that the same may be continued in use for a longer period than would otherwise be possible. For example, in a brush of the proportions indicated in the drawing, by merely adding, so to speak, the comparatively small amount of material represented by the shaded area *e* in Fig. 3, the effective life of the brush would be practically doubled. This is apparent from an examination of Fig. 1, wherein it will be seen that, if the brush were formed with the outer end beveled from *x* to *y*, said brush would have to be discarded when worn down to the line *w—y*. By my improvement the brush may be continued in use until it has worn down approximately to the line *v—z*. I have found that a partial incline or bevel at the outer end of the brush is adequate to enable the spring arm *c* to hold the brush *a* in proper contact with the commutator surface, and also in proper contact with the supporting face of the holder body *b*.

For convenience of description I will refer in the appended claims to that part of the brush indicated by the shaded area *e* in Fig. 3 as a "bulge," which extends above the plane of the adjacent beveled portion, the presence of which bulge is responsible for the added life of the brush.

It will, of course, be understood that the invention relates not only to the improvement in the brush as an article of manufacture, but also to the combination of said brush with a holder of the type illustrated.

I claim:

1. A commutator brush, consisting of an electric conducting block, the inner end of which is adapted to contact with a com-

mutator, the outer end being beveled only partially across the same from the front toward the rear edge, said bevel being in a plane intersecting the plane of the inner end of said brush, said brush having a bulge extending above the plane of the partial bevel at the outer end.

2. A commutator brush, consisting of an electric conducting block, the inner end of

which is formed on an incline to contact 10 with a commutator, part of the outer end being formed on an opposite incline from the front toward the rear edge thereof, said brush having a bulge extending above the plane of said partial incline at said outer 15 end.

ROBERT N. BAYLIS.
